UNITED STATES PATENT OFFICE.

JOSEPH F. COMEE, OF CHICAGO, ILLINOIS, ASSIGNOR TO CAMEL COMPANY, OF CHICAGO, ILLINOIS, A CORPORATION OF MAINE.

DOOR-HANGER.

1,128,293.

Specification of Letters Patent. Patented Feb. 16, 1915.

Application filed May 15, 1914. Serial No. 838,798.

To all whom it may concern:

Be it known that I, JOSEPH F. COMEE, a citizen of the United States, and a resident of Chicago, in the county of Cook and State 5 of Illinois, have invented certain new and useful Improvements in Door-Hangers, of which I do declare the following to be a full, clear, and exact description, reference being had to the accompanying drawing, 10 forming part of this specification.

My present invention has for its object to provide means for sustaining and guiding the sliding doors of railway freight cars, and the invention consists in the features of novelty hereinafter described, illustrated in the accompanying drawing and particularly pointed out in the claims at the 15 end of this specification.

Figure 1 is a view in side elevation of 20 part of a freight car having applied thereto a sliding door equipped with my present invention. Fig. 2 is a view in vertical section on line 2—2 of Fig. 1. Fig. 3 is a view in vertical section on line 3—3 of Fig. 1. 25 Fig. 4, is a detail view in front elevation showing one of the roller supporting brackets and adjacent parts.

A designates the side wall of the freight car along which the door B is adapted to 30 slide. The upper edge of the door B may be held against outward movement in any convenient manner, as for example, by an overhanging bar or plate C that depends a slight distance below the upper edge of the 35 door.

At the door-opening of the car the floor D projects outwardly, as shown in Figs. 2 and 3, and beneath the door-opening and along the path of travel of the door is arranged a series of brackets F that sustain 40 a guide bar G. As shown, each of the brackets F consists of a casting having an upwardly extending member f² adapted to form, with the body of the casting, a channel 45 to receive the bar G, and upon the inner face of each casting is formed a boss or thickened portion f' which serves to bring the channel of the bracket at a distance from the outer face of the car wall. Each of 50 the brackets F is conveniently secured to the car body by means of through bolts 10 and 11, the through bolts 10 serving also to hold the guide bar G in position within the brackets. Inasmuch as the channels of 55 the brackets F are arranged at a distance

from the face of the car wall, the bar G will be held at a distance from the car wall so as to form a space between the upper portion of the bar G and the car wall to receive the inner depending member of 60 a Z-bar E, as clearly shown in Fig. 3 of the drawing. One of the brackets F,—the bracket beneath the left-hand end of the door when the door is in closed position,—is preferably formed with the upstanding 65 portion f⁴ having a cam-shaped inner face adapted to engage the inner member of the Z-bar E and move the door slightly inward as it is brought to closed position.

The Z-bar E is suitably bolted to the lower 70 portion of the car door B and this Z-bar not only serves to guide and to hold the lower portion of the car door against outward movement, but serves also as a track that rests upon a series of rollers K that sustain 75 the weight of the door B. These rollers K are arranged centrally beneath the door B and each roller K is mounted upon a hollow boss m of a casting or roller bracket M.

Each casting or roller bracket M is attached to the guide bar G, as by rivets m'. The upper portion of each of the castings M is formed with an inwardly projecting flange m² that rests upon the upper edge of the bar G, this flange m² serving to relieve 85 in a measure the strain upon the rivets m' and transfer it to the upper edge of the bar G. Through the hollow boss m of each of the castings or roller brackets M passes a pintle m³ and each end of this pintle is 90 preferably headed so as to retain each roller K upon its boss m.

To the lower edge of the car door B are secured a series of supplemental bars R that are preferably angle bars set within grooves 95 formed at intervals along the lower edge of the door and these supplemental bars are attached to the door by through bolts 20 that also pass through the upper vertical member of the Z-bar E. As shown, the lower members of the supplemental angle bars R are riveted as at r to the horizontal member of the Z-bar E. These supplemental bars R serve not only to materially strengthen the Z-bar E, but also serve to 100 brace the inner portion of the Z-bar, which in practice is subjected to severe strains.

Having thus described my invention, what I claim as new and desire to secure by Letters Patent is—

1. In car door mechanism, the combination with a sliding door, of a bar arranged beneath the path of travel of said door, brackets for sustaining said bar, and a series of brackets provided with rollers and secured to the outer face of said bar, said roller brackets having perforated flanged portions and having at their upper ends inwardly projecting flanges extending over the upper edge of said bar, and rivets passing through the flanged portions of said brackets and through said bar.
  2. In car door mechanism, the combination with a sliding door, of a bar arranged beneath the path of travel of said door, brackets for sustaining said bar, and a series of brackets provided with rollers and secured to the outer face of said bar, each
- of said roller brackets being formed of an integral piece of metal provided with an outwardly projecting perforated boss whereon a roller is mounted, a pintle passing through said boss for holding said roller in position thereon and each of said brackets having formed integral therewith laterally projecting perforated flanges and having also formed integral therewith at its upper edge an inwardly projecting flange extending over and resting upon the top edge of said bar, and rivets passing through the laterally projecting flanges of said bracket and through said bar.

JOSEPH F. COMEE.
